RADIATOR HOUSING AND GUARD STRUCTURE

Laurance H. Gillick, Wilmette, Ill., and Ronald W. Madocks, Rosemere, Quebec, Canada, assignors to Vapor Heating Corporation, Chicago, Ill., a corporation of Delaware

Filed Jan. 30, 1958, Ser. No. 712,149

8 Claims. (Cl. 257—295)

The present invention relates to a novel radiator housing and guard structure for railway cars whereby a series of steam or hot water heaters of the radiating type may be supported from the side wall structure of the improved housing in an out-of-the way location beneath the wall trim or seat sills associated with the car wall structure, while at the same time the cold water pipe conduits which conduct service water to the wash basins, toilets and the like are caused to extend along the front wall of the housing in concealed and shielded relationship with respect to the passenger space and passageways of the railway car.

Heretofore it has been customary to cause the elongated sectional radiator structure of a railway car to extend throughout the length of the car in concealed relationship behind a suitable grille which is completely exposed to the car interior along the side wall structure thereof. These grilles frequently become overheated sufficiently to cause discomfort and possible injury to a passenger in the event of physical contact with the grille structure. Also the cold water piping is ordinarily concealed between main and sub-floors of the car or otherwise concealed in the car structure.

The present invention is designed to utilize the cold water piping to prevent discomfort and possible injury to the passengers in the event of their contact with the radiator grille. In this connection the invention contemplates the provision of a supporting structure for steam or hot water radiator units and for the cold water piping of the railway car wherein, by means of a novel assemblage of paneling, shielding and anchoring means, the radiator units and water piping may be supported in substantially coextensive side-by-side relationship so that they extend longitudinally of the railway car along the side wall structure near the base thereof whereby certain advantages are obtained as regards the distribution of heat within the interior of the car, the concealment of the heater units and cold water piping in such manner that the heater units function efficiently to deliver heated air into the car and the cold water piping prevents overheating of the panels of the housing.

The provision of a novel supporting, shielding and concealment arrangement which will accomplish the functions briefly outlined above being among the principal objects of the invention, it is a further object to provide such a structure wherein the major components of the various parts of the radiator and piping supporting structure may be formed of light sheet metal stampings, thereby contributing to economy of manufacture.

A still further object of the invention, in a structure of this character, is to provide an assemblage of supporting structure which may be manufactured and assembled in composite, package-type units at the factory and transported to the scene of installation where the pre-assembled units may be connected together and operatively installed at the time the heater and water pipe installation is effected.

2

Yet another object of the invention is to provide a supporting structure for heater and water pipe installations wherein, after the installation has been made, certain removable concealment panels associated with the assembly of pre-fabricated units are conveniently available and accessible for removal so that access may be had to the radiator units, and to the piping for purposes of inspection, repair, or replacement of parts.

The provision of a heater and piping supporting structure which is attractive in its appearance and which, in its design, cooperates with the natural contour of the railway car to produce certain functional effects wherein heated convection currents of air are directed to the car interior without discomfort to the passengers, are further desirable features which have been borne in mind in the production and development of the present invention.

Other objects and advantages of the invention, not at this time enumerated, will become more readily apparent as the nature of the invention is better understood.

20 In the accompanying drawings forming a part of this specification, one illustrative embodiment of the invention has been shown.

In these drawings:

25 Fig. 1 is a fragmentary front elevational view of a radiator and water pipe supporting housing constructed in accordance with the principles of the present invention.

Fig. 2 is an enlarged sectional view taken substantially along the line 2—2 of Fig. 1.

30 Fig. 3 is a fragmentary perspective view, partly in section, of a portion of the structure shown in Fig. 1.

Fig. 4 is a sectional view taken substantially along the line 4—4 of Fig. 1, and

35 Fig. 5 is an enlarged sectional view taken substantially along the line 5—5 of Fig. 1.

40 Referring now to the drawings in detail and in particular to Figs. 3 and 4, the supporting and housing structure of the present invention is shown as being applied to the inner sheathing or panel arrangement of a conventional wall structure associated with a railway car which may be any one of numerous types as for example, a railway coach, roomette, dining car or the like. Although a specific form of wall structure has been shown herein for illustrative purposes, it will be understood that the present supporting and housing structure is applicable to other types of railway car wall structures. Irrespective however of the particular car side wall structure with which the invention may be associated, the essential features thereof are at all times preserved.

45 The inner car structure includes a lower floor platform 50 which constitutes the tread surface of the car and which is connected to the car side wall assembly 11 in any suitable manner, as for example by welding. Only a portion of the composite car side wall has been illustrated herein, namely the vertical inner wall panel 12 of the 55 dual wall structure usually employed in connection with passenger cars. Trim members such as are shown at 14 and 15, extend along the panel 12 longitudinally thereof and project upwardly in the usual manner.

50 The heater units which are supported by the structure 60 of the present invention are of conventional design, the units being prefabricated, transported to the scene of installation and then connected together in series as shown in Fig. 2 wherein several of the units, each designated at 65 16, are shown. The units 16 may be of the concentric tube type having inner and outer cylindrical tubes 17 and 18 respectively affording an inner lead-in passage 20 for steam or hot water and an annular outer return passage 21. Coupling sleeve devices 22 serve to connect the adjacent ends of the units 16. The outer tubular member 18 of each unit 16 is provided with the usual series 70 of heat dissipating and radiating fins 23. As will be set

forth in more detail subsequently, the heater assembly just described which ordinarily is supported from the wall panel is, according to the present invention, operatively supported in its longitudinally extending relationship to the railway car on a housing including a series of aligned supporting leg members 24, a bottom spacer panel 27, a front side wall 34, hereinafter called an attachment plate, and an upper trim member 60. The said leg members are arranged in a longitudinal row and are themselves supported from the floor 10 and side wall panel 12 of the railway car in a manner that will be described presently. The leg members 24 also serve to support a series of water pipes or conduits 25, three such pipes being shown at 26, the pipes extending longitudinally of the railway car and being arranged in superimposed relationship so that their transverse width within the car structure is maintained at a minimum.

As best seen in Figs. 3 and 4, the various leg members 24 are in the form of relatively narrow strips of formed sheet metal, each strip including a vertical leg proper 30, a horizontal shelf portion 31, and a vertical attachment flange 32. The lower end of each leg proper 30 is supported on the floor 10 while the attachment flange 32 is bolted as at 33 to the trim piece 14 and side wall panel 12. A series of inclined plates 27 extend between the lower ends of the legs 30 and the wall panel 12 and are secured thereto by bolt assemblies 28 and 29.

Mounted on the various leg members 24 and supported thereon a short distance above floor level are a series of elongated attachment plates 34 (see also Figs. 1 and 2), the plates being disposed in end-to-end relationship and being maintained in alignment at their front and rear ends by means of removable splice plates 35 which constitute closures for access openings into the interior of the housing and are bolted as at 37 to offset edges of succeeding attachment plates 34. The junction plates 35 are thus disposed at the "seams" between adjacent attachment plates 34. Each attachment plate 34 thus extends from a region adjacent one of the leg members 24 to a region adjacent the next leg member in the series and the connection between the plates 34 and leg members 24 is made by through-bolt assemblies 40 which, in addition to maintaining the parts 34 and 24 connected, additionally serve to clamp a series of heater-supporting bracket assemblies 41 and a series of saddle clamps 42 in position on the water pipes 25 in such a manner as to firmly clamp the sides of the pipes against the outer faces of the leg members 24.

The various heater-supporting bracket assemblies 41 are best seen in Figs. 2 and 4. They are conventional in design and no claim is made herein to any novelty associated with the same except insofar as they cooperate with the present heater and water pipe supporting structure of the present invention. Each assembly 41 involves in its general organization a shallow U-shaped bracket 43 connected to the front attachment plate 34 and provided with side legs, across which there extends a face plate 44, the face plate being welded to the outer edges of the side legs. Bolted as at 45 to the face plate 44 are a pair of supporting plates 46 and 47 which are L-shaped in vertical cross section and which are arranged in back-to-back relationship. The outer edges of the two plates 46 and 47 are recessed as at 48 and the edge regions of the recess are turned laterally as at 49 in opposite directions to provide a composite semi-cylindrical cradle or seat 50 for reception therein of the sides of the outer cylindrical tube 18 associated with one of the heater units 16. The tube 18 is maintained seated within the cradle 50 by means of a spring clip or strut 51, the ends of which are bifurcated as at 52 and straddle the bifurcations 53 afforded in the brackets 46 and 47 by virtue of the recess 48 and bear against laterally turned portions 54 on the brackets, with the medial region of the spring clip 51 being bowed outwardly and bearing

5

tangentially as at 55 against the outer face of the tube 18. The clips 51 afford a convenient means for detachably clamping the heater structure in position against the various brackets 46 and 47 of the heater supporting assemblies 41. It will be seen therefore that the heater assembly including the various units 16 are supported by the bracket assemblies 41 in operative alignment so that they extend along the car structure in the side regions of the floor 10 slightly elevated above the latter and slightly removed from the vertical wall panel 12 and within the generally rectangular space or enclosure afforded by the floor 10, wall panel 12 and the series of longitudinally extending attachment plates 34.

15

The rectangular space just defined is substantially closed at its upper end by a series of elongated members 60 which, although they are furnished as a part of the novel heater and water pipe supporting structure of the present invention, may be regarded as constituting trim panel members for the railway car side wall 11. Each member 60 is in the form of an elongated channel-shaped sheet metal element having a relatively long transverse side 61 which overlies and is supported upon the various horizontal portions 31 of the leg members 24. The side 61 extends horizontally and is turned laterally to provide a relatively narrow flat vertical inwardly presented edge region 62 which is itself turned laterally to provide a short horizontal reentrant portion 63 which underlies the horizontal portion 61 and the distal edge of which is welded as at 64 to the outer face of the vertical legs proper 30 of the leg portions 24. Interposed between each adjacent pair of legs 24 and immediately underlying the horizontal portion 61 of the various trim members 60, with its outer edge regions nested between the horizontal portions 61 and 63, is a curved insulating member 65 in the form of a sheet of insulating material, the concave side of which faces upwardly. The medial portion of each sheet 65 is supported on a trough-like pan or support 66 the outer edge of which is provided with struck out ears 67 secured by bolt assembly 68 to the legs proper 30 of the leg assembly 24 and the inner edge region of which is provided with similar struck out ears 69 secured by bolt assemblies 70 to the horizontal portion 31 of the leg assemblies.

30

The various trim members 60 are thus arranged longitudinally in end-to-end relationship with their adjacent ends providing "seams" which are concealed by means of seam straps 71 (Fig. 5). The inner edge region of the upper horizontal side 61 of each trim member 60 is flared upwardly as at 72 and the seam strap 71, which follows the contour of the trim member 60 has its inner edge hooked as at 73 (Fig. 5) around the edge 72. The other edge of the seam strap 71 frictionally bears against the lower short horizontal leg 63 of the trim member 60.

35

Referring now particularly to Figs. 3, 4 and 5, the previously mentioned saddle clamps 42 are provided with cradle portions 74 for receiving the various pipes 25 and interconnecting portions 75 between the cradle portions. Bolt assemblies 76 pass through the connecting portions 75 and plate 34 and draw the saddle clamps 42 against the pipes 25 to in turn clamp the latter against the leg members 24. Secured to each leg member 24 in vertically spaced relationship are upper and lower retaining clips 77 and 78 respectively, the various clips serving to retain in position over the pipes 25 a series of aligned trim members 80 serving as an outer cover to conceal the pipes 25 and serving also as a shield to prevent direct contact with the side wall 34. Each shield member 80 is generally U-shape in vertical transverse cross section and each has a vertically extending outer plate 82 and top and bottom walls 83 and 84 respectively. The free edge of the top wall 83 is turned downwardly as at 85 so that it may be hooked, so to speak, behind adjacent brackets 77 on the legs 24 while the free edge of the bot-

75

tom wall 84 is adapted to frictionally engage adjacent brackets 78 so as to securely but removably retain the cover or shield 80 in position over the pipes 25 and on the legs 24 on the outer side of the latter and immediately outwardly of the attachment plates 34. The meeting edges adjacent shields 80 are covered by trim plates 30a.

In an installation of the character set forth above, when the heater assembly is in operation with steam flowing through the passages 20 and 21, heat is radiated forwardly from these elements and that portion of the radiated heat which strikes the attachment plates 34 passes through the plates by conduction but the cold water pipes prevent overheating of the cover and shield structure 80 which enclose the water pipes and constitute the outer face panel of the radiator housing. The manner in which the heater assembly is supported in elevated relationship from the floor 10 and in spaced relationship from the wall panel 12 within the car structure by means of the leg members 24 permits free circulation of air around the heater assembly. Air which enters the elongated and generally rectangular space defined by the attachment plates 34, wall panel 12, spacer plates 27 and upper trim members 60 by flowing through the passage provided for it between the floor 10 and shield member 80 may pass upwardly around both sides of the heater assembly as indicated by the arrows in Fig. 4 and the major portion of the air which passes in front of the heater assembly will flow outwardly again into the compartment or car space through the passage provided for it between the shield plate 84 and the upper trim member 60. The air which flows upwardly behind the heater assembly and between this assembly and wall panel 12 will, in general, flow upwardly through the space existing between the inner edges of the trim members 60 and the wall panel 12 and will be directed outwardly by the trim panels 14 and 15 into the car compartment. The arrangement is such that the heater assembly is entirely concealed within the space provided for it while at the same time the water pipes are not exposed to view nor are they exposed to contact with passersby in the car passageways or compartments of the railway car.

We claim:

1. A prefabricated housing and guard structure for a railway car radiator comprising, in combination, a housing structure extending lengthwise of the car at a side thereof in the region of the floor and provided with a front side wall and air inlet and discharge openings, means located within the housing for supporting a radiator therein, whereby heated air is delivered into the interior of the car, a channel-shaped trim member having lateral flanges removably secured to the outer face of said front wall of the housing to provide a closed but readily opened conduit extending lengthwise of the housing along the outer face thereof and in the region of said radiator enclosed within the housing, and cold water piping enclosed and concealed in said conduit and serving to prevent overheating of the outer face of said channel-shaped trim member.

2. A housing and guard structure for a railway car radiator according to claim 1, wherein said housing includes a plurality of legs and an attachment plate fixed to said legs and defining the upper edge of an air inlet opening and a lower edge of one of said air outlet openings, and wherein the radiator supporting means comprises brackets secured to the inner face of said attachment plate.

3. A housing and guard structure for a railway car radiator according to claim 2, wherein means are provided for removably clamping said cold water piping to the outer face of said attachment plate.

4. A radiator housing and guard structure for a railway car radiator as defined in claim 1 provided with a horizontal trim plate which at least in part overlies said

radiator and has its inner edge spaced from the side wall of the car, thus defining with said car side wall one of said discharge passages for atmospheric air passing upwardly along said side wall behind said radiator and defining with the upper edges of said attachment plates another of said discharge passages for air flowing upwardly through the housing.

5. A radiator housing and guard structure for a railway car radiator as defined in claim 1 wherein each attachment plate has secured thereto along one vertical edge thereof a removable splice plate which overlaps the opposed vertical edge region of the next adjacent attachment plate.

6. In combination with the side wall and floor structure of a railway passenger car, an elongated sectional

10 radiator-type heater assembly extending longitudinally in the compartment in the floor region thereof adjacent said side wall, and a plurality of water-conducting pipes arranged in super-imposed spaced relationship and like- 15 wise extending longitudinally in the car in close proximity to said heater assembly at the level thereof and on the side remote from said side wall, of a supporting structure for said heater assembly and water pipes; said supporting structure comprising a plurality of leg members in the

20 form of narrow strips of sheet metal each having a vertical leg and a horizontal shelf portion, means for securing each leg member to the floor and side wall of the car with the horizontal portion thereof normal to the side wall and the leg normal to the floor with said leg

25 portions in longitudinal alignment in the car, attachment plates bridging the distance between adjacent legs inter- 30 posed between the heater assembly and water pipes and spaced from the floor and horizontal portions of the leg members, said attachment plates being arranged in end-

35 to-end alignment, means removably securing each attachment plate to the next adjacent attachment plate on either side thereof, clamping means for securing said water pipes to each leg, means for supporting said heater as- 40 sembly from the various attachment plates at spaced regions along the heater assembly, and a horizontal trim plate bridging the distance between each pair of adjacent leg members and supported on the horizontal portions thereof.

7. In combination with the floor and vertical side wall 45 of a railway passenger car, a side trim member present- 45 ing an inwardly directed ledge portion spaced above the level of said floor, an elongated sectional radiator-type heater assembly extending longitudinally in the com- 50 partment in the floor region thereof adjacent said side wall and beneath said ledge portion of the trim member, and a plurality of water pipes extending longitudinally in the com- 55 partment in close proximity to said heater assembly at the level thereof and on the side thereof remote from said side wall, of a supporting structure for said heater as- 60 sembly and pipes, said supporting structure comprising a plurality of leg members in the form of narrow strips of metal each having a vertical leg and a horizontal shelf portion, means for securing each leg member to the floor and side wall with the horizontal portion thereof nor- 65 mal to the side wall and the leg portion normal to the floor and all of said leg portions being in longitudinal alignment, attachment plates bridging the distance be- 70 tween the adjacent legs and spaced from the floor and said horizontal portions of the leg members, said attach- 75 ment plates being disposed in a common vertical plane, clamping means for securing the water pipes to said attachment plates on the outside thereof, means for sup- porting the heater assembly on the inner face of said plates and a horizontal trim plate bridging the distance be- 80 tween each pair of adjacent leg members and supported on the horizontal portion thereof, the inner edge of each trim plate being spaced from the wall, thus defining with the side wall a vertical passage for atmospheric air pass- 85 ing upwardly along the side wall of the car behind the

heater assembly, said trim plates being disposed below the level of said ledge portion of the trim member and defining therewith a horizontal passage in communication with the vertical passage for the flow of air issuing from the latter, a horizontal trim plate overlying said heater assembly and defining with the upper edge of said attachment plates a horizontal passage for passage of air flowing upwardly in front of the heater assembly and outwardly into the interior of the car.

8. In a railway car, the combination set forth in claim 7 including, additionally, an insulating sheet underlying each trim plate and coextensive with the latter, and a

supporting plate for each insulating sheet underlying the same and having its opposite edges secured to the supporting leg member and horizontal portion respectively of the adjacent leg member.
